HARRY A. BOWER, OF LOS ANGELES, CALIFORNIA

CONTROL MECHANISM FOR VIBRA HARPS

Application filed October 1, 1931. Serial No. 566,296.

In vibra-harps a vibratile sound is given to the notes, usually by vibrators which operate in or adjacent the resonators. These vibrators usually rotate and give a tremolo effect to the sound being reproduced from the resonators. Usually, with this type of instrument there is no means provided for controlling the rate of the tremolo vibration and, therefore, the instrument has decided limitations in its musical quality and the effects which a musician may obtain from such an instrument are quite decidedly limited.

An object and feature of my invention is a construction by which the musician playing a resonant harp instrument of the xylophone type having resonators may control a tremolo or vibrato of the sound of each and every note and that he may increase or decrease the rate of the tremolo in accordance with the expression he desires to bring out in the composition being reproduced.

In this connection a feature of my mechanical construction giving this control is that I may obtain an instant variation from a retarded to an accelerated tremolo and that when using vibrators of a vibra-harp type of instrument I may obtain musical effects which are impossible in known resonant harp types of instruments.

Another object and feature of my invention is a construction by which I may manually set the controls to have a tremolo or vibrato of a certain definite period and this will be the fundamental period which may be changed by increasing the rate.

Another object and feature of my construction is a setting device for the control mechanism which may be readily shifted to change the rate of the tremolo or vibrato of the resonators and that the rate so adjusted may be maintained. In this connection I have a plurality of different adjustment features allowing setting for relatively fine graduations in rate of tremolo or a coarser regulation of such rate.

In constructing my invention I preferably make use of an electric motor which, through a geared drive, is arranged to operate the rotatable vibrators on the upper

exposed mouths of the resonator tubes. Usually, the tubes are arranged in a row, such tubes being vertical and having the vibrating keys positioned thereabove, and a shaft extends longitudinally of each row of resonators, such shaft being rotatable by the motor, and at each resonator there is a disk-like vibrator. The rate of rotation of these vibrators controls the rate of the tremolo or vibrato of the sound emitted by each resonator. My mechanism comprises a manual control device for changing the speed of the motor so that the vibrators will be rotated at a lesser or a greater speed as desired by the musician.

In the specific construction illustrated, I employ a brake system to give a resistance to the rotation of the motor, this preferably being done by a rotating disk against which brake pads may press. These pads are connected to a yoke and such yoke is slid able, the yoke being normally under a spring pressure to give a considerable resistance or braking effect to the rotation of the motor and, hence, maintaining this at a relatively low speed. I provide a pivoted operating lever, such lever having a long and a short arm on each side of the pivot. The long arm extends in front of the keys and in a position to be engaged by the body of the musician so that by leaning slightly toward the instrument or away therefrom the lever may be operated. A movement of the long end of the lever toward the instrument through the medium of tension links exerts a pull on the yoke and decreases the pressure of the brake pads on the disk and, hence, allows acceleration of the motor and, therefore, of the rate of rotation of the vibrators.

In order that I may obtain a manual setting of the instrument, I provide a fixed bracket secured to the instrument frame, and this has a screw threaded therethrough and such screw may operate along a block attached to the long end of the control lever, and, hence, set this lever in a desired position to allow the motor to operate at a substantially constant speed as adjusted by the musician, which speed may manifestly be

changed to increase or decrease the rate of operation of the vibrators. This screw is provided with a nut lock structure so that it may be locked and thus the desired rate of tremolo cannot be decreased beyond the limit set.

In the construction for giving readily adjustable changes to the speed of the motor and, hence, of the vibrators, which is graduated for a coarse or fine degree of change, I provide a bar secured to the frame of the instrument and extending horizontally therefrom, on which bar I have a rotatable collar, which collar has a series of notches on its different faces, the collar being held on the bar in adjusted positions by a set screw or the like. The collar is provided with a series of serrations different distances apart in which operates a nub on the long end of the control lever. Therefore, a coarse or a fine adjustment of the position of this control lever may be obtained by the engagement of the nub in any one of the serrations, and by rotating the collar a coarse or fine change may be readily made. These serrations, while holding the control lever in a fixed position, do not prevent the musician from pressing inwardly on the manual control end of such lever to further increase the speed of the motor by decreasing the braking pressure.

Various other features of improvement in the art will be apparent from the following description taken in connection with the drawings and the claims.

My invention is illustrated in the accompanying drawings, in which:

Fig. 1 is a plan of a vibra-harp type of instrument equipped with my invention, 40 certain parts broken away;

Fig. 2 is a vertical transverse section on the line 2—2 of Fig. 1 in the direction of the arrows, showing the note keys, the resonators, the vibrators, and the muting bar;

Fig. 3 is a vertical transverse section on the line 3—3 of Fig. 1 in the direction of the arrows, showing the electric motor and part of the control and drive mechanism in elevation;

Fig. 4 is a vertical transverse section showing part of the brake mechanism for the motor in section;

Fig. 5 is a vertical longitudinal section on the line 5—5 of Fig. 4 in the direction of the arrows;

Fig. 6 is a plan with parts shown in section of the manually operated adjusting mechanism for the control lever;

Fig. 7 is a vertical longitudinal detail section on the line 7—7 of Fig. 6 in the direction of the arrows;

Fig. 8 is a vertical transverse section on the line 8—8 of Fig. 6 in the direction of the arrows;

Fig. 9 is a vertical transverse section on

the line 9—9 of Fig. 6 in the direction of the arrows.

The vibra-harps are usually made with supporting rails 11 on which are mounted the sound producing bars 12, these generally being formed of metal. These bars are arranged in two rows and between the rows there is a damper rail 13 having a felt pad 14 which is manipulated usually by a pedal, raising the felt against one end of each of the bars and thereby damping their vibration. Below each bar there is a resonator tube 15 and extending along the top of each row of tubes is a rotatable shaft 16 having a disk-like vibrator 17. These vibrators are of slightly less diameter than the internal diameter of the tube to allow the free rotation and if a particular note is struck the resonator resounds to this note giving a prolonged reproduction of such note and the rotating vibrator gives a tremolo or vibrato effect to such note. Usually the shafts 16 are operated by an electric motor 18, this motor being illustrated as having a reduction drive 19, and a belt drive 20, to the pulleys 21 which rotate the shafts 16.

In my invention I have an extension 22 of the motor shaft, and on this motor shaft I employ a braking disk 23. I also have 95 fan blades 24 which blow air over the motor to keep the motor cool. Connected to a suitable end plate 25 there is a housing 26 which accommodates the disk 23 and part of the fan 24. In this housing there is a partition 27 which supports a rod 28, such rod passing through a perforation 29 in the front end wall 30 of this housing. A collar 31 is slidably mounted on the rod 28. This collar has a projection 32 with a perforation 33 therethrough, through which perforation extends a stud 34 secured in place by a cotter pin 35 and to such stud there is secured a yoke 36 on each end of which there is a felt braking pad 37. The connection of this yoke by the medium of the stud to the collar allows the yoke to turn slightly on the axis of this stud so that the two pads illustrated bear with equal pressure on the face of the braking disk 23. A compression 110 spring 38 coiled on the rod 28 and bearing between the front plate 30 and the collar tends to thrust the collar and, hence, the yoke inwardly, applying the brake with considerable pressure.

A slideable sleeve 39 is mounted on the rod 28 outside of the housing. This is limited in its sliding movement by means of a knurled hand operated nut 40 and a lock wing nut 41. The rod 28 may readily be attached or detached through the medium of its screw threaded end 43 in the partition 27.

The sleeve 39 carries a bracket 44 over which is hooked a link 45, such link being 130

formed of two wires or rods connected to a lug 46 secured to the collar 31. This bracket 44 has a perforation 47 through which extends a threaded finger 48, there being a jam 5 nut 49 to limit the movement of such finger and the finger is secured to the short end 50 of an operating lever designated generally 51, which lever has a long end 52, the lever having a fulcrum at 53, such fulcrum being 10 on a bracket 54 attached to the frame of the musical instrument, (note Fig. 2). This fulcrum may be adjustable on the bracket. For purposes of convenience, the long end 52 of the lever has an arcuate section 55 and 15 has a bolted connection 56 to an outer section 57, to which outer section is added a wood pressure plate 58, this being in a position to be engaged by the lower part of the abdomen of the musician.

20 A tension spring 59 is secured to the end of the short section 50 of the operating lever 51 and attached as indicated at 60 to the end plate 25 of the frame, thus giving an additional tension means to hold the lever 25 with the short end inwardly and the long outer operating end 52 outwardly from the sound bars of the instrument.

In the operation of this part of the instrument, the pressures of the springs normally maintain the more or less certain pressure on the braking disk and will thus maintain the motor normally running at a normal speed, this speed being fairly low so that the tremolo or vibrato effect on the sounds 35 from the resonators have a comparatively short period. The musician playing the instrument may then, if he wishes a faster rate of tremolo or vibrato, lean against the outer end 52 of the operating lever, thus 40 pressing this inwardly and exerting a tension on the link 45 and pulling outwardly on the collar 31 and, hence, releasing the pressure that the braking pads 27 bear on the disk 23. This allows the motor to instantaneously speed up and drive the vibrator 17 45 at a higher rate of speed. The amount of leverage of the lever 51 is so adjusted that a comparatively long arc of movement is necessary for the end 52 to give a small 50 movement to the short end of the lever and thereby controls the motor through a wide range of speed.

A setting adjustment for the lever 51 to set the initial brake pressure is provided by 55 the following mechanism: A two-armed bracket or brace 61 is secured to the front rail 11 of the musical instrument. This bracket has a head 62 with a threaded perforation 63 through which extends a 60 threaded tube 64, such tube having a knurled hand wheel 65 secured to its outer end. The inner end of this tube bears against a block 66 which has a pressure exerting nub 67. A pair of channel-shaped guides 68 (note Figs. 6 and 7) are secured to the block 66 and

hold this centered on the two arms of the bracket 61. The block 66 has a rod 69 secured thereto, which rod extends through the threaded tube 64. The rod is threaded on the outer end 70 and has a knurled hand nut 71 threaded thereon, a lock nut 72, and a washer 73. By this means the block 66 is maintained in a close fitting engagement with the inner end of the threaded tube 64.

The arcuate section 55 of the outer portion 52 of the lever 51 has a collar 74 secured thereto from which there is an upwardly extending plate 75, this plate having a bend as indicated at 76 (note Fig. 8). This plate has an elongated recess 77 into which the operating end of the nub 67 bears. Therefore, by this construction, by operating the knurled hand wheel 65 one way or the other, the threaded tube 64 is forced inwardly or outwardly, carrying the head 66 and the nub 67 and through the medium of the plate 75 and the collar 74 moves the long end of the lever 51 inwardly or outwardly. The threads on the tube 64 are preferably of a coarse pitch to give a quick adjustment. This adjustment may be arranged to set the initial pressure of the braking pads and thus allow the motor to operate at a substantially definite speed but does not in any manner interfere with the further inward movement of the lever due to inward pressure on the end 52. This gives the musician an initial setting to produce the lowest rate of tremolo or vibrato which he desires.

A readily releasable adjuster device 78 employs a rod 79 secured to the frame of the instrument. On such rod there is a collar 80, this being adjustable and having a set screw 81 to clamp such in the adjusted positions. This collar has sets of serrations 82 and 83, these being of different degrees of coarseness.

Any one set may be brought into a position to be engaged by an elongated nub 84 on the portion 55 of the lever 51. A compression spring 85 operating between the instrument and the washer 86 is under compression to thrust outwardly on the collar. The collar may, therefore, readily be adjusted to retain the control arm in any one of the serrations but yet will allow movement of such arm in order to hold the nub 84 in a tight fit in the serrations. An abutment nut 88 is threaded on rod 79 and forms an adjustable limit to the outward movement of collar 80.

A rod 87 has a wedging end accommodated in a deep socket 79' in rod 79, and the opposite end is provided with a tension 125 spring 89 connected to the part 55 of the lever 51. It will be seen, therefore, that by rotating the collar 80 different types of serrations may be brought into engagement with the nub and that various degrees of re-

inement of the adjustment may, therefore, be obtained.

A centrifugal governor 90 is operatively connected to the motor shaft 22. The mechanical connection and operation of this is not illustrated or described, as it is part of an old structure and not a portion of my immediate invention.

An important feature in the artistic playing of the musical instrument is that the control lever 50 may be readily actuated by movement of the body of the musician, without interfering with the operation of the damper rail 13 (which is actuated by a foot pedal). A slight movement of the body of the musician to or from the keys gives a wide variation to the tremolo or vibrato effects.

Various changes may be made in the features of the invention without departing from the spirit or scope thereof as defined in the appended claims.

I claim:

1. A musical instrument having a percussion means to produce musical tones of different pitches, a tubular resonator to respond to each different tone, a vibrator for each resonator, a driving means to operate said vibrators, a setting means to initially set the driving means to operate the vibrators at a certain predetermined period of vibration, and a control means operable by the body of the player of the instrument to increase the rate of drive to decrease the period of vibration.

2. A musical instrument as claimed in claim 1, having in addition an adjusting means to regulate the control means for changing and retaining the driving means to operate the vibrators at predetermined periods of vibration, said adjusting means having a slip connection to allow operation of said control means.

3. A musical instrument having a row of sound bars to produce musical tones by percussion, a tubular resonator to respond to each tone, a vibrator for each resonator, said vibrators being connected together to operate in unison, a motor to drive said vibrators, a pivotally mounted control lever having one end positioned to be engaged by the player of the instrument and the other end having an operative connection to the motor to vary the speed thereof whereby on operation of said lever the player of the instrument may change the speed of the motor.

4. A musical instrument as claimed in claim 3, a bracket connected to the instrument and having an adjusting screw therein, means interengaging between said screw and the lever to position said lever in an initial position to give a relatively slow rate of vibration of the vibrators, said lever being movable to increase the speed of the

motor and hence the rate of vibration of the vibrators.

5. A musical instrument having a row of percussion sound bars to produce tones of different pitches, a tubular resonator positioned beneath each bar to respond to the tone produced by such bar, a vibrator for each resonator, said vibrators being connected together to operate in unison, a motor to drive the vibrators, a control lever pivotally mounted on the instrument having one end extending longitudinally of the sound bars to be operated by the body of the player of the instrument, the other end having a connection to the motor to vary the speed thereof, a setting device comprising a bracket mounted on the instrument and having a screw threaded rod with an interconnection between said rod and the lever to adjust the lever to an initial position to give a relatively slow speed to the motor and hence to the vibrators, said lever being operable to increase the speed of the motor and hence of the vibrators, an adjusting means comprising a rod secured to the instrument having a collar with serrations adjustably mounted thereon, and means on the lever to engage said serrations to adjust the position of the lever independent of the initial setting of the lever, said serrations permitting movement of the lever to change the speed of the motor and hence of the vibrators.

6. A musical instrument having a series of sound bars arranged in a horizontal supporting frame, a resonator beneath each bar, a vibrator on each resonator, a motor drive to all of the vibrators to operate same in unison, a control lever pivoted adjacent one end of the sound bar supporting frame and having an operating end extending substantially parallel to said frame spaced therefrom and adapted to be engaged by the body of the player when playing on the sound bars, and means actuated by said lever to control the speed of the motor and hence of the vibrators.

7. A musical instrument as claimed in claim 6, the means to control the motor comprising a brake disk actuated by the motor, a brake pad, and a connection from the lever to adjust the brake pad in relation to the brake disk.

8. A musical instrument as claimed in claim 6, the sound bar supporting frame having a setting adjustment bracket thereon extending outwardly from the frame, a screw mounted in said bracket, said screw being adapted to engage said lever to adjust the lever to an initial position to determine the lowest vibration of the vibrators, the lever being operable by the movement of the body of a player to release the lever from the end of the screw to accelerate the vibrators.

9. A musical instrument as claimed in

claim 6, a releasable adjuster for the control lever comprising a rod secured to the frame and extending outwardly therefrom, a collar on said rod having a series of notches, the control lever having a nub to engage in any one of the notches, said nub and control lever being readily disengaged from said notches.

10. A musical instrument having a horizontal frame with a row of percussion bars extending therealong, a resonator beneath each bar, each resonator having a rotatable vibrator, a motor having a drive to the vibrators to rotate all of the vibrators at the same speed, said motor having a brake disk and a brake pad to engage therewith, spring means to normally urge the brake pad into engagement with the brake disk, a control lever mounted on a vertical pivot, the control end of the lever extending substantially parallel to one side of the frame and spaced therefrom, the opposite end of the lever having a link mechanism to connect to the brake pad to release the pressure of the brake pad and the brake disk when said lever is pressed inwardly by the body of the instrument player actuating such instrument and thereby varying the speed of the motor and of the vibrators.

30. 11. A musical instrument as claimed in claim 10, a setting adjustment device comprising a bracket secured to the frame extending outwardly, said bracket having a screw operating therein, the bracket forming guides for the movement of the screw, the screw having a pointed end, and means on the control lever to engage such end whereby the initial adjustment of the screw may regulate the pressure of the brake pad on the brake disk.

12. A musical instrument as claimed in claim 10, a releasable adjuster comprising a rod extending outwardly from the frame and having a movable collar thereon, a spring normally urging said collar in one direction, a clamp screw to retain the collar stationary, said collar having a series of transverse notches, the control lever having a nub to engage therein, and spring means to urge the nub into engagement with the notches, said nub being readily released from the notches by a horizontal movement of the control lever.

13. A musical instrument as claimed in claim 10, a setting adjustment device comprising a bracket secured to the frame extending outwardly, said bracket having a screw operating therein, the bracket forming guides for the movement of the screw, the screw having a pointed end, and means on the control lever to engage such end whereby the initial adjustment of the screw may regulate the pressure of the brake pad on the brake disk, a releasable adjuster comprising a rod extending outwardly from the frame

and having a movable collar thereon, a spring normally urging said collar in one direction, a clamp screw to retain the collar stationary, said collar having a series of transverse notches, the control lever having a nub to engage therein, and spring means to urge the nub into engagement with the notches, said nub being readily released from the notches by a horizontal movement of the control lever.

In testimony whereof I have signed my name to this specification.
